UNITED STATES PATENT OFFICE.

CONRAD VAUGHAN, OF CLEVELAND, OHIO, ASSIGNOR TO THE PERMOLD COMPANY,
OF CLEVELAND, OHIO, A CORPORATION OF OHIO.

MOLD.

Application filed February 11, 1924, Serial No. 692,034. Renewed July 22, 1927.

This invention relates to a method of and apparatus for forming castings, and more particularly curved shapes, such as brake shoes, from aluminum or its alloys or any other alloys having relatively high crystallization shrinkage and relatively low fusing point.

Curved shapes, such as brake shoes, have heretofore been cast in molds having a gate at the center of the mold cavity, and the mold so disposed that both ends of the cavity were above the gate. The gates have been relatively large with an elongated opening to the interior of the mold to provide free flow to all parts of the mold, and, in order to cause the metal to flow to the ends of the mold, it has been necessary to pour the metal until the level thereof in the gate was above the end portions of the mold. Consequently the castings had a very large sprue, difficult to trim off and representing a considerable waste incident to the melting of excess metal. In addition, the castings were often defective and liable to crack or break by reason of stresses set up by the freezing of the metal from the ends toward the center and also by the freezing of the metal from the outer portion radially inwardly. In my mold, the metal freezes progressively from one end to the other end and new metal coming through the gate comes at such a rate into the mold cavity that it will compensate for the relatively high solidification shrinkage characteristic of aluminum alloys.

It is an object of the present invention to provide a method of casting curved shapes by which such castings may be made which are free from internal stresses and, therefore, of superior strength and durability, and in which the castings are formed with true and even surfaces.

A further object of the invention is to provide a mold for casting curved shapes with a minimum excess of metal in the sprue.

A further object is to provide a mold from which the casting may be quickly removed and which ejects the casting in such a manner that the hot casting is held against distortion.

With the above and other objects in view, the invention may be said to comprise the method and apparatus as illustrated in the accompanying drawings hereinafter de-

scribed and particularly defined in the appended claims, together with such variations and modifications thereof as will be apparent to those skilled in the art to which this invention appertains.

Reference should be had to the accompanying drawings forming a part of this specification, in which

Figure 1 is a front elevation of the mold with the sections in closed position.

Fig. 2 is a central vertical section through the mold on line 2—2, Fig. 1.

Fig. 2 is a perspective view of that portion of the mold which forms the face of the casting.

Fig. 3 is a front elevation of the mold with the sections in open position.

Fig. 4 is a side elevation of the mold.

Fig. 5 is a side elevation of the casting.

Fig. 6 is a section through the casting taken on line 6—6, Fig. 5.

In forming castings in accordance with the present invention, the mold is preferably so mounted that the curved cavity thereof is tilted upwardly at such an angle from the horizontal that one end of the mold cavity is lowermost, and the mold is provided with a gate adjacent the upper end of the cavity so that the molten metal flowing through the gate flows toward the lower end of the cavity and the metal freezes progressively from the lower to the upper end of the casting, so that opposing stresses are not set up in the metal, due to the casting being retained in the mold longer than necessary for it to set. Also, to facilitate quick removal of the casting from the mold, I have provided an ejecting mechanism, more fully described hereinafter, which will permit the mold to be opened while the casting is quite hot and yet will hold the casting from distortion.

Referring to the accompanying drawings, the mold is mounted in a suitable box-like casing 1, which has a bottom wall 2 and a rear wall 3 at right angles thereto and end walls 4 and 5, the mold being detachably secured to the forwardly sloping top of a supporting stand 6.

The mold consists of a fixed back member 7 detachably secured to the central portion of the casing 1 and side sections 8 and 9 mounted in the casing for movement toward

- and from each other and adapted to be positioned in engagement with each other to complete the mold cavity over the back member 7. The back member 7 of the mold is detachably secured at the center of the casing 1 to the bottom and back walls 2 and 3 thereof by means of screws 10, and has its outer face curved to form the outer wall of the mold cavity. The side sections 8 and 9 have base portions 11 and 12 slidably mounted upon the bottom and back walls 2 and 3 of the casing 1, and are retained in the casing and guided by guide strips 13 and 14 secured along the lower edge of the bottom 2 and the upper edge of the back wall 3 of the casing, respectively. The inner portions of the side sections are adapted to engage opposite sides of the fixed mold section 7 and have overhanging outer portions adapted to engage with each other centrally over the back member 7 and close the inner side of the mold cavity when the side sections are adjusted into engagement with the fixed mold section 7. At the upper ends thereof the sections 8 and 9 are provided with complementary tapering grooves leading to the recessed portions and which, when the sections are secured together, form the gate and funnel-shaped sprue cavity 15.
- 30 Figs. 5 and 6 show the brake shoe casting which is formed in the mold, this casting having a wide flanged outer portion 16 forming the engaging face and a web 17 projecting inwardly from the outer portion. The outer flanged portion 16 is formed against the back member 7 of the mold and the complementary cavities of the side sections are shaped to form the inner faces of the flanges and the web portion 17. The shoe is formed at one end with an eye 18 to receive a pivot pin, and adjacent the center with an elongated opening 19 to receive a guide pin, the openings 18 and 19 being reinforced with suitable bosses. At the end opposite the eye 18 the web of the casting is formed to provide spaced ears, forming a crotch 20 in which a link may be pivoted.
- The outer face of the wide flanged outer portion 16 of the casting is formed against the fixed mold member 7, and the side sections 8 and 9 of the mold are so formed that when the sections are brought together a mold cavity corresponding to the complete casting is formed. The section 8 carries a core pin 21 which is slidably mounted in a transverse opening therein and is adapted to be pushed into the mold across the cavity to form the eye 18 at the end of the casting, the section 8 carrying also a slidably mounted core pin 22, shaped to form the elongated opening 19, recesses being formed in the inner faces of the mold sections around the core pins to form the bosses. The crotch 20 is formed by means of a core bar 23 which is mounted upon the inner face of the mold section 9 and lies, when the mold is closed, partly in a groove 24 in the section 9 and partly in a groove 25 in the section 8. The groove 24 is deeper than the groove 25, and the core bar 23 has a thickened outer portion fitting in the groove 24. The core bar 23 is retained in the groove 25 by means of a block 26 which fits in an elongated slot 27 in the bar 23. The block 26 is rigidly secured to the bottom of the groove 24 by means of screws 28 and has a retaining flange 29 at its outer end which engages in recesses along the edges of the slot 27 on the inner face of the bar 23, the outer face of the block 26 being flush with the inner face of the bar 23. The inner end of the core bar 23 is centered with respect to the mold cavity and has its inner end rounded to form the bottom of the groove between the ears forming the crotch 20. The core bar 23 is provided with a rack 30 on its under side, which is engaged by a pinion 31 which carries a hand wheel 32 by means of which the core bar may be moved in or out, the inward movement of the core bar being limited by the block 26 which is so positioned that when the core bar is in its innermost position it will be in proper position for forming the crotch 20 in the casting. The core members 21, 22 and 23 are all adjusted into the mold cavity before pouring and are withdrawn from the casting before the mold is opened, each of the core members being slightly tapered to facilitate their withdrawal from the casting.
- 35 For clamping the mold sections 8 and 9 together with adequate pressure, screws 33 are attached thereto and project through slots 34 in the opposite end walls 4 and 5 of the mold supporting casing. For moving the screws 33 longitudinally to apply pressure to the mold sections, each screw has a nut 35 which has an external groove 36 fitting in the slot 34, whereby the nut may be rotated, and has a thrust bearing against the end wall to hold it against longitudinal outward or inward movement in clamping the mold sections and separating them. Each nut 35 has a crank handle 37 by means of which it may be rotated to shift the mold section, and an oppositely extending weighted counterbalance arm 38 which enables the nuts to be given a rapid spin to impart quick movement to the mold sections.
- 40 The mold sections are all detachably mounted in the supporting casing so that they may be readily removed and replaced by mold sections for castings of different size or shape. To facilitate the quick removal of the side sections, the screws 33 are connected to the sections by means of pivots 39, and the grooves 36 are considerably wider than the thickness of the end walls of the casing so that when the nut is loosened the screws may be readily swung up out of the slots 34 and freed from the casing.

When the metal is poured, it enters through the funnel-shaped sprue cavity 15 and flows rapidly to the lowermost end of the casting, the mold cavity being progressively filled from the lowermost end to the gate which is near the highest portion of the mold cavity, just sufficient metal being poured into the sprue cavity and through the gate to insure flow to the extreme top of the mold cavity. The metal is thus caused to freeze progressively from the lower to the upper end of the casting, the shrinkage of the metal during cooling being progressively taken up by the flow of hotter metal from above.

It will thus be seen that by properly proportioning the sprue cavity and the gate or opening between the sprue cavity and the mold cavity the sprue cavity may be very small and contain very little excess metal, as it is only necessary to furnish a sufficient head to completely fill the mold and to provide molten metal for feeding only a small portion of the metal in the casting near the gate.

Difficulty has heretofore been experienced in forming from aluminum alloys castings of shapes similar to that shown herein, due to the fact that the central portion of the wide flanged outer portion 16 of the casting does not cool as fast as other thinner portions of the casting. This sometimes results in uneven outer surfaces, due to shrinkage of this central portion caused by slower freezing of this portion and interference with flow of metal thereto by freezing of adjacent thinner portions. To avoid this difficulty I make the longitudinal central portion of the back mold member 7 a good conductor of heat and outside the longitudinal central portion I make this back member a poor conductor of heat. This I accomplish by leaving a central strip 40 along the center of the inner face of the member 7 uncoated or coated with any suitable coating, such as a graphite composition, which will not appreciably retard conduction of heat. Outside the central strip 40, which is located opposite the web of the casting, I apply preferably a suitable coating 41, such as a clay mixture, which is a poor conductor of heat. By this means the cooling of the thicker portion of the casting is facilitated with respect to the adjacent flanges, and the cooling of the adjacent flanges retarded, thus permitting the thicker portion of the casting to solidify first and preventing shrinkage away from the mold, as the necessary feeding of the inner portion of the casting is accomplished by the incoming hot metal from the gate, the mold, as mentioned above, being designed so that the casting freezes progressively from one end to the gate.

An important feature of the invention is

the provision of means whereby the mold may be opened while the casting is still quite hot without danger of marring or deforming the casting. To this end means is provided for holding the casting upon the curved backing member while the side sections are separated so that the casting is held against distortion when it is still quite hot. To this end upper and lower ejector pins 42 and 43 adapted to engage the ends of the casting and a middle ejector pin 44 adapted to engage the middle of the casting are rigidly secured to the side wall 5 of the supporting casing and project through the section 9, the pins being of such length that their inner ends are flush with the inner surface of the section 9 when the same is in operative position. The lower ejector pin 43 lies opposite the core pin 21 which forms the eye 18 in the lower end of the casting, and is of sufficiently greater diameter than the pin 21 to engage solidly with the boss surrounding the eye 18 in the casting.

In opening the mold, the core pins 21 and 22 are withdrawn and the mold section 8 is retracted quickly by the crank 37 and the nut 35, and the casting is held against the mold by the core pins. The core 23 is then withdrawn by turning the hand wheel 32, and the mold section 9 is retracted by operation of the similar crank 37 and nut 35, the fixed ejector pins 42, 43 and 44 holding the casting in place upon the fixed section 7 of the mold while section 9 is being withdrawn therefrom. The casting is thus held against distortion while the mold sections are being retracted and may be removed from the mold.

Furthermore, it is to be understood that the particular forms of apparatus shown and described and the particular procedure set forth are presented for purposes of explanation and illustration and that various modifications of said apparatus and procedure can be made without departing from my invention as defined in the appended claims.

What I claim is:

1. A mold for casting shapes having a longitudinal curvature, comprising a fixed section adapted to form the outer, convex face of the curved casting, side sections movable toward and from the fixed section and adapted to be clamped together over the fixed section to form the mold cavity, means for supporting said sections in a position such that the mold cavity is inclined downwardly from one end to the other, and means forming a gate at the top of the mold.

2. A mold for casting brake shoes comprising a fixed section having an inner curved face, side sections adapted to be clamped together over said fixed section, said side sections cooperating with the fixed section to form the flanges of the brake shoe

- and with each other to form the web thereof, core pins carried by one of the sections for forming holes in the web, and means for retaining the casting on the fixed section 5 while one of the side sections is being withdrawn.
3. A mold comprising a pair of movable side sections having complementary depressions to form a mold cavity, said sections 10 having meeting edges adapted to contact along the center plane of the casting and extending outwardly along said plane to form flat faces, alined grooves in said flat faces extending into said mold cavity, and a core 15 plate slidible in said grooves when said sections are assembled and adapted to extend into said mold cavity.
4. A mold comprising movably mounted side sections having complementary depressions adapted when the mold is assembled 20 to form a mold cavity and flat faces adapted to contact along the center plane of the casting, said flat faces having alined grooves, a core plate slidible in the groove in one of 25 said side sections, said core plate projecting beyond the flat face of said side section and adapted to fit in the groove of the other section, means carried by the section on which the core plate is mounted for shifting 30 the core plate to move the inner end thereof into or out of the mold cavity, and means for limiting the movement of the core plate.
5. In a mold, in combination, a mold supporting casing having a bottom and back 35 wall, a stationary mold section detachably secured to said bottom and back wall, a pair of mold side sections slidably mounted in the casing on opposite sides of the fixed mold section, said slidable and fixed mold sections 40 cooperating when in assembled relation to enclose a mold cavity, means for moving said slidable mold sections, and means for securing said slidable mold sections in cooperative relation with said fixed mold section.
- 45 6. A mold for casting longitudinally curved shapes having convex outer faces, which comprises a mold casing, a mold section having a concave face and secured to the mold casing, mold sections slidably 50 mounted in the casing for movement toward and from said concave section, guides on the casing for guiding said movable sections, means carried by said movable sections for engagement with the casing to shift said 55 sections, said mold casing being mounted as an entirety in a supporting stand, so that one end of the longitudinally curved mold cavity is substantially lowermost.
7. A mold for casting a longitudinally curved shape having a convex outer face 60 comprising a mold section provided with a concave inner face for forming said convex face of the casting, mold sections on either side of said concave section and having recesses therein to cooperatively form with 65 said concave mold section the complete mold cavity, said concave mold section having portions thereof coated to retard the escape of heat from the casting, and having a portion to relatively facilitate the escape of 70 heat.
8. A permanent mold having its cavity forming wall coated in part with a substance to retard heat transfer and coated in part with a substance to relatively facilitate heat 75 transfer.
9. A permanent mold adapted for use in forming castings from metal of relatively high crystallization shrinkage and relatively low freezing point, said mold comprising a plurality of mold sections, said mold sections cooperating to enclose a mold cavity, the wall of said mold cavity being coated in part with material to retard heat transfer, and coated in part with material to relatively 80 facilitate heat transfer.
10. A permanent mold for use in forming castings having a longitudinal curvature from metal of relatively high crystallization shrinkage and relatively low melting point, 85 said mold comprising, in combination, a back mold section having an inner curved face adapted to form the outer convex face of the curved casting, side mold sections arranged to be disposed in assembled position over said back section, said side sections being provided with complementary recesses forming with said back section a mold cavity inclining downwardly from one end to the other, said recesses forming also a relatively 90 small sprue cavity extending upwardly from adjacent the upper end of said mold cavity and a relatively small gate intermediate and connecting said mold and sprue cavities, means for securing said mold sections in 95 molding position, and ejecting means associated with one of said side sections whereby a casting may be disassociated from said section.
- In testimony whereof, I hereunto affix my 100 signature.

CONRAD VAUGHAN.
